UNITED STATES PATENT OFFICE.

ELBRIDGE R. HOLMES, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

WEFT DETECTOR FOR LOOM TRANSFERRER MECHANISM.

Application filed April 24, 1925. Serial No. 25,642.

This invention relates to weft detectors for looms and more particularly to the type of detector carried on a regularly moving transerrer arm, such as shown in prior Patent No. 1,372,316.

In detectors as set forth in said patent there is slidably mounted on the transerrer a plunger or pin which is moved into the path of a cam lever by a detector at the time weft exhaustion is indicated. It has been found that as exhaustion approaches, the detector strikes the plunger but with insufficient force to move the same its full distance, with the result that faulty indication is given to the replenishing mechanism.

It is the general object of my invention to provide means to prevent improper indication even though the plunger be struck by the detector prior to the time when indication should be given.

It is a further object of my invention to provide means for locking the indicating plunger in its normal position and releasing it by a second plunger actuated by the detector.

With these and other objects in view which will appear as the description proceeds, my invention resides in the combination and arrangement of parts hereinafter described and set forth in the claims.

In the accompanying drawings, wherein I have shown one form of my invention,

Fig. 1 is a side elevation of a multi-color weft replenishing mechanism having my invention applied thereto.

Fig. 2 is a detail rear view of the rocking lever which resets my improved plunger, looking in the direction of arrow 2, Fig. 1.

Fig. 3 is an enlarged rear elevation of the transerrer arm,

Fig. 4 is a view similar to Fig. 3 but with parts in section,

Fig. 5 is a vertical section on line 5-5 of Fig. 3,

Fig. 6 is a fragmentary view similar to Fig. 4 but with the parts in a different position, and

Fig. 7 is a detail top plan view of the locking plunger forming part of my invention.

Referring more particularly to the drawings it will be seen that I have provided a

loom frame 10 on which is mounted a multi-color weft replenishing mechanism 11 having vertical slides 12 which control bobbin 55 releasing devices 13. A box motion controlled lever 14 is pivoted as at 15 to the stand 11 and has secured thereto a slotted collar 16 having driving connections with a color slide 17 which is moved laterally to be 60 in operative position with respect to the upper and lower lugs 18 and 19, respectively, of one or another of the slides 12. Said color slide is movable in bearings 20 to control any of said slides but controls only one 65 at a time. The slide is rocked in the bearings 20 by a lever 21 and link connection 22 and said link is pivotally connected as at 23 to a lever 24 pivoted at 25 to the frame of the replenishing mechanism. Whenever the 70 horizontal arm of the lever 24 is depressed the color slide will be given a movement to elevate the slide 12 which it controls.

The transerrer arm 26 is pivotally mounted on a stud 27 secured to the stand 11 and is 75 reciprocated by a rising and falling link 28 actuated from a cam not shown. Pivotally mounted on a fixed pivot 29 is a trip lever 30 having a pad 31 for a purpose to be described and having connected thereto as at 80 32 the lower end of a link 33 the upper end of which extends through a lug 34 and has secured thereto a collar 35. Interposed between said collar and the lug 34 is a compression spring 36 which serves normally to 85 hold the trip lever in raised position as shown in Fig. 1. A collar 37 on link 33 limits upward movement of lever 30. The matter thus far described is substantially the same as set forth in Patents No. 1,030,748 90 and No. 1,372,316.

My improvements relate more particularly to the detector mechanism which controls the lever 24 and as shown in Figs. 3 to 6 I have provided the transerrer arm 26 95 with an offset foot 40 having a bobbin head engaging portion 41 and a yarn engaging portion 42. That portion of the transerrer arm which connects with the foot is solid as indicated at 43 and slot 44 extends vertically 100 through the hammer between the portions 42 and 43. The lateral walls 45 of the slot 44 have extending therebetween a plunger support 46 integral therewith.

The side walls 45 are each provided with an upstanding ear 47 supporting a pin 48 on which is pivotally mounted a lever 49. Extending laterally from the inner end of said lever 49 is a finger 50 integral therewith and positioned to engage the pad 31 when the transerrer is moved downwardly by the link 28. The other end of said lever 49 has pivotally connected thereto as at 51 a detector 52 of the side slip type having a detecting surface 53 to engage the bobbin and having a stop screw 54 in the upper end thereof to engage a stop 55 on the arm 49 to limit motion of said detector 52 toward the portion 42. Lever 49 is provided with a bore 56 which receives a plunger 57 pivotally connected to the detector as at 58. A compression spring 59 is interposed between the lever 49 and a shoulder 60 formed on the plunger 57 to hold the screw 54 against stop 55 and position the detector 52 so that the detecting surface 53 is offset laterally from the pivot 51 of said lever 49. Lever 49 is also provided with a depending arm 61 through which extends an opening 62 for a purpose to be described.

An indicating plunger 70 having an enlarged head 71 is guided in the portions 43 and 46 and also extends through bore 62 of the arm 61. A spring 72 is interposed between the head 71 and the arm 61, to hold the arms 49 in the position indicated in Fig. 4 and also tending normally to move the pin 70 toward lever 24. Said pin 70 is provided with a circumferential groove 73 in the lower side of which fits a ball lock 74. Said ball is held in position by the releasing plunger 75 guided in the support 46 and held in normal position to the left as shown in Fig. 4 by a compression spring 76. Said release pin 75 is formed with a projecting end 77 and is provided with a circumferential notch 78 similar to the notch 73 and has extending therethrough a vertical slot 79 across which extends a pin 80 secured to said pin 75. The lower face of the support 46 receives a screw 81 which has an upwardly extending tip 82. Spring 76 holds the pin 80 against the tip 82 to position the pin 75 substantially as shown in Fig. 4 with the notch 78 therein laterally offset with respect to the ball lock 74. The screw 81 is slightly larger than the ball to permit the latter to be inserted in place.

The lower end of the lever 24 is provided with a cam face 83 and as shown in Fig. 2 is provided with a second cam face 84.

In operation the link 28 will reciprocate to lower the transerrer arm 26 every second pick of the loom to cause engagement of the tip 31 by finger 50 on lever 49, and so long as sufficient yarn is present the detector 52 will be held against movement along the bobbin and spring 36 will be compressed. When insufficient yarn for con-

tinued weaving remains on the bobbin the detector will move along the bobbin as indicated in dotted lines in Fig. 3 and will move the lock pin 75 from the position shown in Fig. 4 to the position shown in Fig. 6 with the notch 78 therein directly under the ball 74. The latter will therefore drop from its normal position and spring 72 will move the plunger 70 to the right to project beyond the end of the transerrer as shown in dotted lines in Fig. 3. When this occurs the transerrer is in its lowest position and the plunger 70 is below the cam face 83. Consequently when the transerrer arm 26 is raised the plunger will move along the cam face 83 to give the lever 24 a clockwise oscillation to rock the color slide 17 and the slide 12 corresponding to the active shuttle will be raised. As the transerrer arm continues to move upwardly the plunger 70 will enter a space 85 in the lever 24 which will permit the latter to move back to the position shown in full lines in Fig. 1 in a manner similar to that set forth in the aforesaid Patent No. 1,372,316. Because of the fact that the ball 74 engages a cylindrical portion of the plunger 70 when in the notch 78 it will be possible for said plunger 70 to be restored to normal position as the transerrer arm is raised to move the plunger in contact with cam face 84 on the arm 24. As soon as the notch 73 appears above the ball 74 compression spring 76 will move the lock plunger 75 to the left and the parts will be restored to their normal position shown in Fig. 4. A check nut 86 on the plunger 70 limits outward movement of the latter.

From the foregoing it will be seen that I have provided a weft detector of the type mounted on a regularly reciprocating transerrer arm so designed that the plunger 75 can receive slight motion from the detector 52 without permitting movement of the actuating plunger 70 and that the latter will not move to operative position until the movement of the detector 52 is complete and the lock pin 75 has been moved its full distance. It will also be seen that the spring 72 serves the double function of holding the lever 49 in normal position and also of moving the plunger 70 to operative position.

Having thus described my invention it will be apparent that changes and modifications may be made therein by the skilled in the art without departing from the spirit and scope of the invention, and I do not wish to be limited to the details herein disclosed but what I claim is:

1. In a weft detector for loom weft replenishing mechanism, a regularly reciprocating transerrer arm, an indicating lever pivotally mounted on the replenishing mechanism, a weft detector mounted on the transerrer arm and movable therewith, a plunger

mounted on the transerrer arm and tending normally to move toward the indicating lever, and a ball lock to retain said plunger away from the indicating lever, 5 said lock being released by the detector at substantial exhaustion of weft so that said plunger may move toward the indicating lever.

2. In a weft detector for loom weft replenishing mechanism, a regularly reciprocating transerrer arm, an indicating lever for the replenishing mechanism, a detector lever pivotally mounted on the transerrer arm, a detector mounted on said detector lever, 10 a plunger slidably mounted on the transerrer arm, a lock normally holding said plunger out of operative position with respect to the indicating lever, and resilient means interposed between the detector lever and the plunger tending normally to hold said detector in inoperative position and tending to move said plunger into operative position with respect to the indicating lever when said lock is released by the detector 15 upon indication of substantial exhaustion.

3. In a weft detector for loom weft replenishing mechanism, a regularly reciprocating transerrer arm, an indicating lever for the replenishing mechanism, a detector 20 mounted on the transerrer arm and movable therewith, a pair of plungers mounted on said transerrer arm, and a ball lock interposed between said plungers, one of said plungers being engaged by the detector 25 when the latter indicates substantial exhaustion to release the lock, and resilient means to move the other plunger into operative position with respect to the indicating lever.

4. In a weft detector for loom weft replenishing mechanism, a regularly reciprocating transerrer arm, an indicating lever for the replenishing mechanism, a detector mounted on and movable with the transerrer arm, a pair of substantially parallel plungers slidably mounted on and movable with said transerrer arm, said plungers having notches therein normally out of alignment, a ball lock between said plungers received 45 by one of the notches, one of said plungers being engaged and moved by the detector when the latter indicates substantial weft exhaustion to release said ball lock, and resilient means to move the other plunger into 50 operative relation with respect to the indicating lever.

5. In a weft detector for loom weft replenishing mechanism, a regularly reciprocating transerrer arm, an indicating lever 55 for the replenishing mechanism, a detector mounted on and movable with the transerrer arm, a plunger for the indicating lever slidably mounted on said transerrer arm, a second plunger for said detector also mounted on said transerrer arm, said

plungers having notches therein normally out of alignment, a ball lock interposed between said plungers and normally entering the notch of one of the plungers and engaging the other plunger, resilient means 70 tending to move the plunger having the notch normally occupied by the ball into operative relation with respect to the indicating lever, said detector engaging the other plunger at indication of weft exhaustion to 75 move the notch therein into position to receive the ball whereby to release the first plunger so that the resilient means may move the same into operative position with respect to the indicating lever, and additional resilient means acting on the plunger engaged by the detector tending normally to move the notch therein out of position with respect to the ball.

6. In a weft detector for loom weft replenishing mechanism, a regularly moving transerrer arm, an indicating lever pivotally mounted on the replenishing mechanism, a weft detector supported by and moving with the transerrer arm, a pair of 80 spring pressed plungers, one for said indicating lever and one for said detector, and a ball lock located between and contacting with both of said plungers at all times, 85 said plungers having normally offset notches 90 therein, one of which normally receives the ball lock and the other of which is movable to register with the ball lock by the weft detector at indication of weft exhaustion.

7. In a weft detector for loom weft replenishing mechanism, a regularly moving transerrer arm, an indicating lever pivotally mounted on the replenishing mechanism, a weft detector supported by said transerrer arm, a pair of spring pressed 100 plungers slidably mounted on the transerrer arm, one of said plungers for the indicating lever and the other of said plungers for the detector, a ball lock intermediate the 105 plungers and normally in contact with both of said plungers, said plungers each having a notch for the reception of the ball lock, said notches being normally offset and the plunger for the indicating lever being normally locked by having the ball in the notch thereof, the plunger for the detector being movable by the latter at indication of weft exhaustion to move the corresponding notch 110 in registry with the ball to release the plunger for the indicator, and positive 115 means to move the plunger for the indicating lever to move the notch therein back in registering position with the ball to release the plunger for the detector.

8. In a weft detector for loom weft replenishing mechanism, a regularly reciprocating transerrer arm, an indicating lever for the replenishing mechanism, a detector supported by and movable with the transerrer arm, a pair of plungers mounted on 120

and slidale in said transfferer arm, one of said plungers being normally out of operative position with respect to the indicating lever and being movable into operative position with respect thereto and the other plunger being engageable by the detector when the latter indicates weft exhaustion

and movable by said detector, and a lock interposed between said plungers and movable by either plunger to lock the other ¹⁰ plunger.

In testimony whereof I have hereunto affixed my signature.

ELBRIDGE R. HOLMES.
